(57) **CLAIM**

The ornamental design for a battery box with controller, as shown and described.

DESCRIPTION

FIG. 1 is a perspective view of a battery box with controller, showing my new design, where the controller is shown separately in order to disclose aspects of the design that would be obstructed when combined;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the battery box with controller where the battery box is shown separately in order to disclose aspects of the design that would be obstructed when combined;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the drawings depict portions of the battery box with controller that form no part of the claimed design.
